STANLEY EDWARD TALBOT, OF WIMBLEDON, ENGLAND

GLARE-PREVENTING DEVICE

Application filed November 17, 1927, Serial No. 233,953, and in Great Britain December 9, 1926.

This invention relates to vehicle headlights, particularly the headlights of motor road vehicles, and refers to headlights of the known kind incorporating means for preventing side glare and restricting the angle of diversion of the light beam, consisting of a plurality of rings of varying depths arranged one within another concentrically at the front of the lamp and located within the body of the lamp behind the lamp window or lens, the deepest rings being arranged towards the centre of the lamp and the narrowest rings towards its periphery.

With a lamp having side-glare preventing means as above described, the light rays are projected through the annular spaces between adjacent rings, and the angle of diversion of the light beam projected from the reflector through any one of said annular spaces, is determined by the location of the front edge of the outer encircling ring of said space in relation to the rear edge of the adjacent inner ring. That is to say, if an imaginary straight line be drawn passing through points corresponding to said inner and outer edges, such line, extended beyond the front of the lamp, corresponds to the angle of greatest diversion of the light rays projected through the annular space.

Hitherto, in lamps incorporating side-glare preventing devices of the kind set forth, all the annular rings have been equally spaced apart or the said spaces between adjacent rings have been varied without conforming to any predetermined order, rule or sequence.

It will be apparent from the foregoing remarks that the angle of greatest diversion of a light beam projected through one of the annular spaces, and corresponding to the straight line aforesaid passing through the front and rear edges of adjacent rings, is governed by two factors, namely, the space between the adjacent rings and the depth of said rings. If one of said factors be altered without corresponding adjustment of the other factor, the aforesaid line of greatest diversion will be accordingly of a greater or lesser angle, and if the depth of the rings varies from widest rings in the centre to nar-

rowest rings at the outside, whilst the spaces between adjacent rings remain constant, such arrangement having already been proposed, then the shafts of light projected from different annular spaces vary as to the angle of diversion, those spaces towards the periphery of the lamp giving the greatest angle of diversion.

The present invention, providing means for preventing side-glare from a headlamp, and for restricting the angle of diversion of the light beam, consisting of annular rings of varying diameters concentrically arranged within one another at the front of the lamp as hereinbefore described, is characterized in that the consecutive annular spaces between the rings vary in width according to the depths of the rings which divide said spaces from one another. That is to say, as the depths of the rings decrease in size from those nearest the centre of the lamp to those nearest the outside, so the annular spaces between adjacent rings also decrease in width in the same proportion. In other words, the annular space between a certain ring and the adjacent larger one is in definite proportion to the depth of the said larger ring, the same rule applying for each annular space.

Such decrease in the depth of the rings and width of spaces, may also be proportionate to reduction in the concavity of the reflector towards its circumference.

It will be apparent, therefore, that as the annular spaces between the said rings consecutively diminish in width from the centre of the lamp towards the periphery thereof in relation and proportion to the width of the adjacent rings, and on account of this compensation between the one and other, if an imaginary straight line as previously described is drawn through each annular space through points corresponding to the inner and outer edges of each ring, all the said imaginary lines so drawn in either an upward or downward direction will be parallel, and since these imaginary lines represent the angles of greatest diversion for the respective spaces the angles of greatest diversion will be the same in the case of each space

and the light beams projected will be screened to an equal degree simultaneously by each ring.

The front edges of the rings preferably are flush with one another in a line parallel to the window or lens of the lamp.

The space constituting the area within the innermost ring is closed, and the arrangement of the whole assembly of rings is such that no direct rays from the illuminant are projected in front of the lamp at any point, the entire beam from the lamp being reflected light. The rings themselves do not interfere to any appreciable extent with horizontal reflected rays. The inner closed ring aforesaid may be an auxiliary ring whose depth is or is not in proportion to that of the other rings as hereinbefore described.

In order that the invention may be the more readily understood a device of practical construction in accordance therewith is illustrated in the accompanying drawings, wherein:—

Figure 1 is a vertical section through said complete device, a lamp to which it is applied being indicated by dotted lines.

Figure 2 is a plan view of a support for the rings, hereinafter described.

Figure 3 is a plan view of the ring assembly.

Figure 4 is a plan view of the rings and their support assembled together, a lamp being indicated by dotted lines.

Figure 5 is a front view of the device showing same applied to a base ring.

Figure 6 is an edge view of the front interengaging ring portions shown in Figure 5.

Figures 7 and 8 are front and edge views respectively of a glass panel with frosted portions hereinafter described; and,

Figure 9 is a face of said glass panel applied to the device, the latter being shown in dotted lines.

Corresponding parts in the several views are indicated by the same reference numerals.

In the construction shown in the said drawings, the rings 1 are supported by a pair of substantially triangular plates 2 (omitted in Figure 1 for the sake of clearness) longitudinally arranged within the lamp and formed with slots for the engagement of the rings 1, said plates 2 being perpendicular to 55 and intersecting one another, and each being slotted at its centre for the engagement of the other. Preferably the said plates are arranged each at approximately 45 degrees to the horizontal. The longest sides of the 60 said plates 2 are at the front of the lamp, and may be flush with the front edges of the rings 1 and the remaining sides 3 of said plates converge towards the source of illumination, said plates being cut away at their 65 inner ends as indicated at 4 to accommodate

the said illuminating means, for instance, an electric lamp 5.

The triangular plates 2 divide up the lamp front into a number of equal segments, a convenient number being four, as shown, and, if desired, any number of said segments in order to further reduce the angle of diversion of rays therefrom may contain additional arcuate plates or interrupted rings 6 serving the same purpose as the rings 1 aforesaid and interposed therebetween, said plates being of such a depth and so located between the rings that they adhere to the principle of the invention as above set forth. Said additional plates 6 constitute rings which are discontinued so that they are not present in one or more of the said segments, for instance, in the segment 7 as shown in the drawings.

It is desirable in connection with the head-lamps of motor road vehicles to restrict the angle of diversion of the light rays which extend upwardly and to the sides whilst not restricting the angle of diversion of the downwardly directed rays to the same extent, so that the road is illuminated near the vehicle, and in order to produce such an effect the additional arcuate plates or interrupted rings 6 aforesaid may be continued through the upper and side segments whilst not being present in the lowermost segment 90 or segments.

In connection with the said lower or other segment or segments into which the additional arcuate plates do not extend, for instance, the segment 7 shown in Figure 5, there may be provided means which, whilst not interrupting the outwardly directed rays whose angle of greatest diversion is limited by the rings in the manner aforesaid, limits the angle of the downwardly directed rays which are projected from said segment or segments and pass across the axis of the complete ray pencil to the other of said axis; for instance, the rays upwardly directed from the lower segment 7. Such means may consist of a clear glass panel 8, shown in Figures 7, 8 and 9, fitted in front of the rings 1 contained in said segment, said glass panel having arcuate frosted ground or similar translucent strips 9 formed upon it, one for each of the spaces 10 between adjacent rings. The inner edge of each of the said frosted or ground strips 9 is coincident with the innermost ring 1 defining the space 10 with which said strip co-operates, but said strip is not so wide as the said space 10, so as to leave a clear outer portion 11 for the passage of the rays. In this case the frosted or ground strips 9 serve to interrupt some of the inwardly extending rays, the angle of diversion of said rays being governed by the width of said strips, as indicated by the dotted lines *a* (Figure 1), but being ground or frosted they do not totally obscure and waste all the interrupted light, although they could be made opaque, is so 115 120 125 130

desired. Conveniently, the frosted or ground strips 9 may be of such a width as to make the extreme inwardly directed rays *a* (Figure 1) substantially parallel to the extreme outwardly diverging rays *b* projected from the 5 diametrically opposite part of the lamp front.

The said glass panel 8, triangular-shaped in accordance with the configuration of the segment 7 with which it co-operates, may be attached in position by screws or by any other 10 suitable means. For instance, it may be attached by a screw 12 at its apex to a metal or other disc 13 which closes the front end of the innermost ring, and at its curved periphery by a clip 14 fixed to an annular frame ring 15, by which latter the complete 15 ring assembly and the triangular plates 2 are fixedly carried, as hereinafter described.

The invention as above described can be 20 embodied in a lamp as a component part thereof or it may be in the form of an attachment for a lamp. In the latter case, as shown in the drawings, the frame ring 15 to which the rings and triangular plates are fixedly attached is detachably, hingedly or otherwise carried by a base ring 16, which latter seats over the front flange 17 of the lamp reflector 18, the said annular frame ring 15 having projecting lugs 19 or the like 25 adapted to engage under spring clips 20 on the base ring by rotating the said frame ring 15. Or, the base ring 16 may be eliminated, the frame ring 15 being hinged or otherwise mounted, or adapted to be mounted directly 30 to the front flange 17 of the reflector to engage therewith by partial rotation in the said manner. Conveniently, in order to connect the frame ring 15 to the base ring 16 or to the lamp reflector in such a manner as to allow of the locking of said frame ring by partial 35 rotation thereof, there may be provided on the said base ring or flange of the lamp reflector a fixed arcuate rod 21 lying on a circumference thereof, on which is mounted to rotate thereupon and to slide therealong, a 40 collar 22 to which is attached the frame ring 15. An additional springy tongue may be provided on one of the engaging parts adapted to engage a raised projection on the other 45 part and effect a wedge-locking action by the relative rotation as aforesaid, such a device 50 not being shown in the drawings.

In order to provide additional support for the rings, and for the arcuate plates if employed, there may be provided a number of thin wire rods 23 extending across the lamp front and attached to the said rings and plates.

The rings 1 may be finished to a dull black 60 on one or both sides, although the inner under sides of the rings at the top of the lamp or in the top segment may be silvered or nickelized to reflect light downwardly on to the road surface.

In order that it may be clearly seen that

the widths of the spaces between the rings are in definite proportion to the depths of the rings, as hereinbefore described, reference is directed to Figure 1 of the drawings, and the following description. As shown, the 70 complete ring assembly is of cone formation, the apex of the cone outline *d* drawn through the inner edges of all the rings being on the axis of the ring assembly at the point marked *d*¹ in Figure 1, at or in close proximity to the light source. The imaginary lines *f* 75 represent the extreme light rays between the light source and the front edge of the lamp reflector, the cone outline *d* of the ring assembly being coincident with or adjacent to and parallel with said imaginary lines *f*.

The imaginary point *c* is on the axis of the ring assembly and positioned from the flat front of said assembly at one-sixth of the distance between the front of said assembly and the point *d*¹ although it could be any other proportion of said distance. The imaginary lines *e* drawn from the point *c* meet the plane of the flat front face of the ring assembly at the same points as the cone 80 outline *d*.

As will be seen by the arcs *g* in the lower half of Figure 1, the width of the space between any two rings is equal to the distance *h* between the front edge of the larger of said two rings and the point where the line *e* intersects said larger ring. Since said distance *h* is in direct and constant proportion to the total depth *i* of the larger ring in the case of each of the spaces, therefore all of the 90 spaces have a width in direct and constant proportion to the depths of the respective rings. In the upper half of Figure 1 additional interrupted rings 6 are shown as hereinbefore described, positioned between the 95 rings illustrated in the lower half of said view.

The device according to the invention, whilst adhering to the feature of equal angles of greatest diversion from all the spaces, affords large spaces towards the centre of the lamp front for the propagation of a maximum amount of light, whilst at the same time it does not interfere with the passage 100 of direct light from the light source to the reflector.

Moreover, in the construction illustrated in the drawings, the glass lamp front may be opened for cleaning without disturbing the said device, whilst access may be gained to the interior of the lamp by simply swinging the device forwardly about its hinge connection, after giving it a partial rotary movement.

I claim:—

The combination of a headlight and anti-glare means therefor, said means comprising a plurality of concentrically arranged rings of different lengths, the longest of which is the innermost ring, each adjacent exterior 130

ring being shorter than the interior ring adjacent thereto, and the distance between adjacent rings varying in definite proportion to the lengths of said rings.

5 In testimony whereof I have affixed my signature hereto this 26th day of October, 1927.

STANLEY EDWARD TALBOT.

10 A ring having a plurality of rings of varying sizes, the outer ring being the largest and the inner ring being the smallest, the outer ring being shorter than the inner ring, and the distance between adjacent rings varying in definite proportion to the lengths of said rings.

15 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

20 The inner ring of a ring having a plurality of rings of varying sizes, the outer ring being the largest and the inner ring being the smallest, the outer ring being shorter than the inner ring, and the distance between adjacent rings varying in definite proportion to the lengths of said rings.

25 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

30 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

35 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

40 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

45 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

50 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

55 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

60 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.

65 The outer ring of a ring having a plurality of rings of varying sizes, the outer ring being the largest and the inner ring being the smallest, the outer ring being shorter than the inner ring, and the distance between adjacent rings varying in definite proportion to the lengths of said rings.
